UNITED STATES PATENT OFFICE.

MORRIS OFFENBERG, OF PITTSBURG, PENNSYLVANIA, ASSIGNOR TO HERCULES LIGHT & CHEMICAL CO., OF PITTSBURG, PENNSYLVANIA.

MANTLE-HOLDER.

932,636.

Specification of Letters Patent. Patented Aug. 31, 1909.

Application filed May 21, 1907, Serial No. 374,895. Renewed January 26, 1909. Serial No. 474,331.

To all whom it may concern:

Be it known that I, MORRIS OFFENBERG, a subject of the Emperor of Germany, residing at Pittsburg, in the county of Allegheny and State of Pennsylvania, have invented certain new and useful Improvements in Mantle-Holders, of which the following is a specification, reference being had therein to the accompanying drawing.

10 This invention relates to mantle holders, and the invention has for its primary object to provide a simple and inexpensive holder, which will not break the mantle due to the expansion and contraction of the holder.

15 Another object of this invention is to provide a strong and durable mantle holder in which a mantle can be easily and quickly fastened.

20 A further object of this invention is to provide a mantle holder that can be constructed from a single piece of metal, the holder being designed whereby the top of the mantle will be fully protected.

25 A still further object of this invention is to provide a novel mantle holder that will not interfere with the light or rays given off by the same.

30 A still further object of this invention is to provide a mantle holder to present a neat appearance, and will be free of all danger of injury by the heat from the mantle.

35 With the above and other objects in view which will more readily appear as the invention is better understood, the same consists in the novel construction, combination and arrangement of parts to be hereinafter more fully described, and then specifically pointed out in the appended claim.

40 Referring to the drawing forming part of this specification, like numerals of reference designate corresponding parts throughout the several views, in which:—

45 Figure 1 is a front elevation of my improved mantle holder, Fig. 2 is a side elevation of the same, Fig. 3 is an enlarged cross sectional view of the holder, Fig. 4 is a plan of the mantle holder, and Fig. 5 is a bottom plan.

50 To put my invention into practice, I construct my improved mantle holder from a single piece of metal preferably a disk which has its peripheral edges cut and sheared, as

at 1 providing a plurality of radially disposed slits. The piece of metal is also cut and sheared, as at 2, to provide a strap 3, 55 said strap during the formation of the holder being bent upwardly, to form a loop by which the holder is suspended from a suitable support 4.

60 The piece of metal when stamped and bent provides a crown 5 for shielding the upper edges of a mantle 6, said mantle being fixed in the groove 7 of the holder and resting upon the slotted breast 8 thereof. The slotted breast when subjected to the heat of 65 the mantle expands and firmly supports the upper edges of the mantle 6 in the groove 7 of the holder, although the expansion and contraction of the holder will not interfere with the mantle 6 or the support 4, as the 70 supporting means, namely the strap 3 is loosely mounted upon the support. In constructing a mantle holder wherein provision is made for the expansion and contraction thereof, I have dispensed with the breaking 75 of mantle holders due to this cause, and increased the longevity of mantles.

I do not care to confine myself to the specific shape of the holder or to the material from which the same is constructed, and I 80 desire it to be understood that such changes in the size, proportion and minor details of construction as are permissible by the appended claim, may be resorted to without departing from the spirit and scope of the 85 invention.

What I claim and desire to secure by Letters Patent, is:—

90 The combination with a mantle and the support thereof, of a mantle holder, said 90 holder being constructed of a single piece of metal cut to provide a central strap or loop for suspending said holder from said support, said holder having peripheral slotted edges bent to provide a crown for said mantle, a circumferentially arranged groove, and a breast for supporting the upper edges of 95 said mantle in said groove.

In testimony whereof I affix my signature in the presence of two witnesses.

MORRIS OFFENBERG.
